3,372,866 KEYPUNCH MACHINE

Francis Allen McLean, Nixon Knowlton, and Nicholas E. Steiner, Hawkesbury, Ontario, Canada, assignors, by mesne assignments, to Grant Darbyson, Ontario, Canada
Filed Oct. 18, 1965, Ser. No. 496,952
11 Claims. (Cl. 234—123)

ABSTRACT OF THE DISCLOSURE

An electric keypunch machine for cutting notches in the edges of tabulating cards. Cards to be punched are placed on a reciprocable card table of the machine. The cards are punched by means of pivotable punches each of which is controlled by a key. When a key is depressed, the corresponding punch is held stationary, and as the punches are in the path of the card table the card is cut as the card table reciprocates. If the key is not depressed, the punch pivots freely upon engagement with the card and the card is not cut.

This invention relates to a machine for punching cards or the like and in particular to an electric keypunch machine for cutting notches in the edges of tabulating cards.

An object of the invention is to provide a simple, efficient and reliable keypunch machine for use with tabulating or classification cards such as the kind having perforations in marginal areas of the cards. The perforations are usually divided into digit fields with the perforations of each field identified by the numerals 1, 2, 4 and 7. A card is coded by cutting a notch in the card from a selected perforation to the adjacent edge of the card, and a stack of coded cards can be sorted by inserting a needle into selected perforations. The cards which have been notched at the needle location drop out of the stack.

Another object of the invention is to provide a keypunch machine having an efficient automatic key elevating mechanism that is adapted to either automatically elevate selected coding keys or else to permit them to remain depressed during operation of the machine.

A further object of the invention is to provide a keypunch machine having a simple, efficient and reliable timed drive mechanism.

A preferred embodiment of the invention is illustrated in the accompanying drawings, wherein like reference numerals refer to similar parts, and wherein:

FIG. 1 is a perspective view of a machine constructed in accordance with the invention;

FIG. 2 is a fragmentary perspective view, partly broken away, showing the principal components of the machine of FIG. 1;

FIG. 3 is a sectional view taken along the line 3—3 of FIG. 2 showing an electric motor and a solenoid actuated brake;

FIG. 4 is an elevational view, showing the relationship between a timing cam and a related microswitch;

FIG. 5 is an elevational view, partly in section and partly broken away, taken from the righthand side of the machine shown in FIG. 1;

FIG. 6 is a sectional view taken along the line 6—6 of FIG. 5, showing a field of four punches in alignment with grooves in a die;

FIG. 7 is a sectional view taken along the line 7—7 of FIG. 5, showing two adjacent correction keys and related structure;

FIG. 8 is a fragmentary sectional view, showing the relationship between a depressed coding key and related structure after a card has been punched;

2

FIG. 9 is a fragmentary sectional view similar to FIG. 8 showing an elevated coding key;

FIG. 10 is a fragmentary sectional view, showing details of an automatic key elevating mechanism in its cancellation condition with a key lever in its operative condition at the start of a cycle of operation;

FIG. 11 is a fragmentary sectional view similar to FIG. 10 showing a key lever that has been returned to its inoperative position by the automatic key elevating mechanism; and

FIG. 12 is a sectional view taken along the line 12—12 of FIG. 11 showing the relationship between two adjacent key lever actuators and related key levers.

Referring to the drawings, a preferred form of a keypunch machine is indicated by reference numeral 10, and its principal components include a frame 11, a keyboard 12, a reciprocable card table 13, an automatic key elevating mechanism 14 and a drive mechanism 15. The card table 13 is movable between a rest position and a working position during operation of the machine, and a card positioned on the card table is notched by selected punches which are held stationary during operation of the machine. The machine 10 is particularly adapted for cutting notches in the edges of tabulating or record cards, such as the kind mentioned above having perforations in marginal areas.

Frame

The frame 11 includes a rectangular base 16 and two opposed upstanding side walls 17 and 18 which are secured to the base. A cover 19 encloses the machine. Paper chips which are formed during a punching operation fall through an opening 20 in the base. It is intended that the table on which the machine rests have an open receptacle directly below the opening 20 for receiving paper chips.

Keyboard

The keyboard 12 includes coding keys 22, manual correction keys 23, repeat/cancel levers 24 and an operation key 25. The keys 22 are arranged, for example, in four rows and are divided into columnar digit fields containing four coding keys 22 which are marked with suitable indicia such as the numerals 1, 2, 4 and 7, respectively. Each coding key 22 is secured to the outer end of a key lever 26 which is pivotally secured intermediate its end to a transverse shaft 27 the ends of which are removably secured to the side walls 17 and 18. The key levers 26 are of one-piece construction and have inner end portions 26a which are aligned in relatively deep grooves 28 of a transverse bar 29. The ends of the transverse bar 29 are fixed to the side walls 17 and 18. Each inner end portion 26a terminates in a slender projection 26b which is adapted to hold a related punch stationary during operation of the machine, as will be explained.

The key levers 26 are movable between an inoperative position with the coding keys 22 elevated as shown in FIG. 5, and an operative position with the coding keys 22 depressed as shown in FIG. 8. Secured to the underside of the transverse bar 29 are flat, outwardly extending springs 30, one for each key lever 26. The springs 30 bear against cam surfaces 26c to permit the key levers 26 to assume only the inoperative or the operative positions. The key levers 26 are progressively longer from rear to front, as shown in FIG. 5.

The manual correction keys 23 are secured to levers 31 which are pivoted at their outer ends about the transverse shaft 27. There is one correction key 23 and hence one lever 31 for each field. Each lever 31 includes a flat, rectangular portion 31a having at its outer end a pair of opposed flanges 31b extending at right angles therefrom. The rectangular portion 31a rests upon the upper edges

of a related field of key levers 26, but in order to show the above structure more clearly the single lever 31 shown in FIG. 2 has been pivoted forwardly until it is nearly vertical. In its usual horizontal position, however, each lever 31 spans the related field of key levers 26 so that whenever any one coding key 22 of the field is depressed the related lever 31 is raised slightly (see FIG. 8). If the coding key 22 was depressed erroneously it can be elevated again by depressing the related correction key 23.

The relationship between the correction keys 23, the levers 31 and the key levers 26 is shown in FIG. 7. The structure associated with the extreme right-hand field is shown in solid lines, and the structure of the next adjacent field is shown in chain dotted lines. The flanges 31b of each lever 31 are bounded by and are in sliding contact with two outer key levers 26, namely those which are respectively associated with the numeral 7 and numeral 1 coding keys of the field. Inside the area bounded by the flanges 31b are two inner key levers 26, namely those associated with the numeral 4 and numeral 2 coding keys of the field. Proper alignment is preserved by sleeves 32, 33 and 34 which are slipped onto the transverse shaft 27. The sleeves 32 separate adjacent fields, the sleeves 33 separate the inner key levers 26 from each other, and the longer sleeves 34, one at each side of the keyboard, respectively separate the extreme right and left-hand key levers 26 from the adjacent side walls of the frame.

The automatic key elevating mechanism 14 is controlled by the repeat/cancel levers 24 which are pivoted about a fixed transverse shaft 35 which extends between the side walls 17 and 18. The repeat/cancel levers 24 are movable between a repeat position (see FIG. 5) and a cancel position (see FIG. 10); their movement is limited by a fixed transverse bar 36 which also extends between the side walls 17 and 18. The upper ends of the repeat/cancel levers 24 are exposed so that they can be grasped by hand, and their lower ends terminate in rollers 24a. Additional structure associated with the automatic key elevating mechanism will be described in detail below.

The operation key 25, when depressed, closes a normally open microswitch 37.

Card table

The card table 13 is a solid, generally rectangular bar that extends between the side walls 17 and 18 of the frame. End plates 13a are fixed to the opposite ends of the card table 13, and the card table is supported by a transverse circular shaft 38 which extends through openings 39 in the end plates 13a. The ends of the shaft 38 are fixed to the side walls 17 and 18. The card table 13 is pivoted about the shaft 38 and is adapted to reciprocate between a rest position and a working position, as will be described. Secured to the front of the card table 13 is a die 40 which is formed with a series of narrow notches 41. Punches 42, each corresponding to a related coding key 22, are pivoted about the shaft 38 and are aligned with the notches 41 in the die 40. Each punch 42 is generally rectangular, is formed from a flat plate, and has a working end 42a which is adapted to cut notches in an edge of a card positioned on the card table 13. Each punch 42 has an accurately formed circular opening 43 near its lower end for receiving the shaft 38, and the punches 42 are kept in spaced parallel alignment by engagement of their upper end portions 42b with the notches 41 in the die 40 (see FIGS. 2 and 5). This alignment is perhaps most clearly shown in FIG. 6. The punches 42 are freely movable to and fro about the shaft 38. Inward travel is limited by a fixed transverse circular shaft 48 which extends between the side walls 17 and 18, and outward travel is limited by engagement with the inner ends of the key levers 26 (see FIGS. 8 and 9).

FIGS. 1 and 5 show a typical card 44 positioned on the card table. A transverse rectangular guide 45, preferably formed of clear plastic material, keeps the card flush against the die 40. The guide 45 is supported at its ends

by slender supporting arms 46 which are fixed at their lower ends to the end plates 13a and at their upper ends to the guide 45. The lower edge of the card 44 is supported by the upper edges of the punches 42 as shown in FIG. 5, and the card 44 is properly aligned in the machine by engagement with an eccentric disc 47 that can be removably attached to any one of tapped openings 47a in the cover 19 (FIG. 1).

Drive mechanism

10 The drive mechanism 15 includes an electric motor 49 which is secured to the base 16. The motor 49 is operatively connected to a rotatable transverse drive shaft 50 through a worm gear 51 and a pinion 52. The ends of the drive shaft 50 are journaled for rotation in the side walls 17 and 18, and the drive shaft 50 carries an eccentric roller 53 at each of its opposite ends, just inside the side walls 17 and 18. Each roller 53 is in rolling contact with a flat rear face of the related end plate 13a. The card table 13 is inwardly biased by a pair of springs 54 which are secured at one end to the card table 13 and at their opposite ends to posts 55 which extend from the side walls 17 and 18, respectively.

15 The motor 49 is provided with a solenoid actuated brake 56 which is automatically released when the motor 49 is energized. Referring to FIG. 3, the brake 56 includes a solenoid 57 and a spring loaded pressure disc 58. The solenoid 57 is energized contemporaneously with the motor. Fixed to the outer end of the motor shaft is a disc 59 having a brake lining 60, preferably of cork, on its inner face. Normally the pressure disc 58 is pressed firmly against the lining 60, but when the motor 49 and the solenoid 57 are energized the pressure disc 58 is pulled inwardly by the solenoid 57 thereby permitting the motor 20 to run freely. Conversely, when the motor 49 and the solenoid 57 are de-energized, the pressure disc 58 again bears against the lining 60 thus braking the motor 49. Additional braking force is provided by the drive mechanism itself; note that the connection between the motor 49 and the drive shaft 50 is through the worm gear 51 and the pinion 52.

25 During one complete revolution of the drive shaft 50, the card table 13 moves forwardly from its rest position to its working position and then rearwardly to its rest position, under the influence of the eccentric rollers 53. It is therefore necessary that the rotation of the drive shaft 50 be limited to exactly one revolution, and this is accomplished as follows. A timing cam 61 is fixed to the drive shaft 50 and is engagable with a roller 62 of a microswitch 63. The microswitch 63 is supported by a bracket 64 secured to the base 16, and is normally open. The relationship between the timing cam 61 and the roller 62 is shown in FIG. 4 (the card table is in the rest position), and in this position the circuit of the microswitch 50 55 63 is open since the roller 62 is not engaged by the timing cam 61. Both microswitches 63 and 37 are in the electrical input circuit of the motor 49 and when either microswitch is closed the motor 49 is energized. Thus, upon depressing the operation key 25, the microswitch 37 closes and the motor 49 is energized, causing the drive shaft 50 to rotate. After the drive shaft 50 rotates through a small angle, the roller 62 is engaged by the timing cam 61 and the microswitch 63 closes thereby keeping the motor 49 energized even after the microswitch 37 opens. Eventually the roller 62 drops off the end of the timing cam 65 61, and the microswitch 63 opens thereby de-energizing the motor and reactivating the brake. The point at which the roller 62 is disengaged from the timing cam 61 is such that the drive shaft 50 comes to rest in its original or rest position, with the timing cam 61 and the roller 70 62 again in the position shown in FIG. 4.

Automatic key elevating mechanism

75 The automatic key elevating mechanism 14 can be set in either a repeat or a cancellation condition by adjust-

ing the repeat/cancel levers 24. When a repeat/chance lever 24 is pulled outwardly (repeat position) as shown in FIG. 5, related keys remain depressed after a cycle of operation so that a number of cards can be identically coded without resetting the keys. Conversely, when a repeat/cancel lever 24 is pushed inwardly (cancel position) as shown in FIGS. 10 and 11, related keys are automatically elevated after a card is punched. This is accomplished as follows. Referring to FIGS. 2 and 5, a longitudinal slot 65 is formed in each side wall 17 and 18. A transverse rectangular bar 66 reciprocates in the slots 65 during operation of the machine, and the ends of the bar 66 are pivotally connected to links 67 that are driven by cranks 68 which are respectively fixed to the opposite ends of the drive shaft 50.

Resting upon the upper surface of the bar 66 are elongated, generally flat longitudinal levers 69 having inner ends 69a which curve upwardly slightly and outer ends 69b of a more pronounced upward curvature. The levers 69 are held in position by spring loaded screws 70, and there is one lever 69 for each field of key levers 26. Each lever 69 is associated with a key lever actuator 71. The key lever actuators 71 are U-shaped (viewed from the front) and are pivotally supported by a fixed transverse shaft 72 which extends between the side walls 17 and 18. Each key lever actuator 71 includes a plane, rectangular upper portion 71a and two opposed V-shaped flanges 71b. Normally the key lever actuators are in the position shown in FIG. 5 with their upper portions 71a held against the upper end of a stop member 73 by springs 74. The springs are secured at one end to one flange 71b of each key lever actuator 71 and at their opposite ends to a fixed transverse shaft 75 which extends between the side walls 17 and 18. Rectangular openings 76 (see FIG. 2) in the upper edge of the stop member 73 accommodate the springs 74 (see FIG. 12), and spacers 77 and 78 respectively separate the key lever actuators 71 from the side walls of the frame and from each other.

Referring now to FIG. 10, the mechanism is shown in its position at the start of a cycle of operation. The key 22 has been depressed, and the related key lever 26 is in its operative position and is in close proximity to the related key lever actuator 71. The repeat/cancel lever 24 is in the cancel position, and its roller 24a rides up onto the curved outer end 69b of the lever 69 causing the opposite end 69a to press firmly against the lower end of the key lever actuator 71. During operation of the machine, the bar 66 at first moves outwardly, towards the front of the machine so that the end 69a springs upwardly after disengaging the key lever actuator 71. After reaching the limit of its outward travel, the bar 66 reverses its direction and begins to move inwardly. In FIG. 11 the end 69a of the lever 69 has struck the key lever actuator 71, causing it to pivot in a counter-clockwise direction when viewed from the right. The inner edge of the upper portion 71a of the key lever actuator 71 engages the key lever 26 causing it to return to its inoperative position where it is held in place by the spring 30. The bar 66 continues to move upwardly until it reaches its inward limit, the end 69a drops under the flange 71b, and the key lever actuator 71 is returned to the position shown in FIG. 10 by the spring 74. After reaching its inward limit, the bar 66 moves outwardly again for a short distance, and eventually comes to rest with the end 69a in the position shown in FIG. 10, directly under the lower end of the key lever actuator 71. As shown in FIG. 12, each key lever actuator 71 spans four key levers 26 of a field, so all key levers 26 of the field are automatically returned to their inoperative positions if the related repeat/cancel lever is in the cancel position. When the repeat/cancel lever 24 is in the repeat position, as shown in FIG. 5, the end 69a of the lever 69 does not engage the related key lever actuator 71 during operation of the machine, so the related key levers 26 remain in their original positions.

Operation of machine

At the start of a cycle of operation the mechanism of the machine is in the rest position shown in FIG. 5. The card 44 is positioned on the card table 13, and the card table 13 is at the inward limit of its travel. The keys 22 of FIG. 5 are elevated, and consequently the projections 26b on the inner ends of the key levers 26 do not engage the related punches 42. When the motor 49 is energized the drive shaft 50 rotates, and the eccentric rollers 53 rotate in a clockwise direction when viewed from the right. This causes the card table to pivot outwardly towards the front of the machine. The card 44 engages the working ends 42a of the punches 42, but since the punches are not held by the projections 26b of the key levers 26, they are free to move outwardly with the card table and the card is not punched. FIG. 9 shows the relationship between the above parts when the card table is at the limit of its outward travel. After the card table reaches its outward limit, its motion is reversed and it finally comes to rest at its rest position. If a key 22 is depressed, however, the related punch 42 is held stationary by the projection 26b on the related key lever 26. Thus, as the card table moves outwardly the card is notched by the working ends 42a of those punches which have been held stationary. This is shown in FIG. 8. The card table has moved to the limit of its outward travel, and the card has been notched by the punch 42, forming a small rectangular chip of paper 79.

What we claim as our invention is:

1. A machine for punching a card or the like comprising:
a frame;
a reciprocable card table which is pivotally secured to the frame along a transverse pivot axis and which is movable between a rest position and a working position;
a plurality of normally movable punches having working ends which are adapted to cut away portions of a card positioned on the card table, the punches being individually pivotal about said pivot axis, and the working ends being movable between a first position within the path of the card table and a second position outside the path of the card table;
punch selection means for holding selected punches stationary with their working ends in said first position during operation of the machine, whereby the card is punched as the card table is moved from the rest position to the working position.
2. A machine as claimed in claim 1 wherein the punch selection means comprises a plurality of manually settable key levers having inner ends which are engagable with the selected punches, each key lever being of one-piece construction and being pivoted intermediate its ends.
3. A machine for punching a card or the like comprising:
a frame having two opposed side walls and a fixed shaft extending between the side walls;
a card table which is pivotally secured to the shaft and which is movable between a rest position and a working position;
a die which is carried by the card table;
a plurality of normally movable punches having working ends which are adapted to cut away portions of a card positioned on the card table, the punches being pivotally secured to the shaft and being aligned for sliding engagement with openings in the die, the working ends being movable between a first position within the path of the card table and a second position outside the path of the card table;
a plurality of manually settable key levers having inner ends which are adapted to hold selected punches stationary with their working ends in said first position during operation of the machine, whereby the card is punched as the card table is moved from the rest position to the working position.

4. A machine as claimed in claim 3 wherein the working ends of the punches are separated from the die by at least the card thickness when the card table is in the rest position.

5. A machine as claimed in claim 4 wherein the key levers are each of one-piece construction and are pivoted intermediate their ends, and wherein the punches are normally movable independently of the card table except when engaged by the card.

6. A machine for punching a card or the like comprising:

a frame having two opposed side walls and a fixed shaft extending between the side walls;
a card table which is pivotally secured to the shaft and which is movable between a rest position and a working position;
a die which is carried by the card table;
a plurality of normally movable punches having working ends which are adapted to cut away portions of a card positioned on the card table, the punches being pivotally secured to the shaft and being aligned for sliding engagement with openings in the die, the working ends being movable between a first position within the path of the card table and a second position outside the path of the card table;
a plurality of manually settable key levers having inner ends which are adapted to hold selected punches stationary with their working ends in said first position during operation of the machine, whereby the card is punched as the card table is moved from the rest position to the working position; and
a plurality of pivoted correction key levers which rest upon upper end portions of the key levers and which are adapted to disengage the key levers from related punches when said correction key levers are pushed downwardly.

7. In a machine for punching a card or the like, the machine including a frame and a plurality of key levers which are pivoted intermediate their ends and which are movable between an operative and an inoperative position; automatic key elevating means that is optionally settable in a repeat condition and in a cancellation condition, said means being adapted, in the cancellation condition, to engage selected key levers which are in the operative position and return them to the inoperative position during operation of the machine, said means comprising:

a transverse bar that is carried by the frame and which reciprocates inwardly and outwardly during operation of the machine;
a plurality of spaced longitudinal levers which are pivotally secured to the transverse bar intermediate their inner and outer ends;
a plurality of repeat/cancel levers which are optionally settable in a repeat position and in a cancel position, the repeat/cancel levers when in the cancel condition being adapted to depress the outer ends of related longitudinal levers to thereby raise the inner ends thereof, the raised inner ends of said longitudinal levers being operatively connected to key levers which are in the operative position and adapted to automatically return said key levers to the inoperative position during operation of the machine.

8. Automatic key elevating means as claimed in claim 7 wherein there is a longitudinal lever and a repeat/cancel lever for every group of four key levers, and wherein there

5 is a pivoted key lever actuator for each group, each actuator being engagable with the raised inner end of a longitudinal lever of the group, and each actuator being adapted to return the key levers of the related group from the operative position to the inoperative position when said actuator is engaged by the raised inner end of a related longitudinal lever during operation of the machine.

9. A machine for punching a card or the like comprising:

a frame;
a reciprocable card table carried by the frame and movable between a rest position and a working position;
a plurality of normally movable punches having working ends which are adapted to cut away portions of a card positioned on the card table, the working ends being movable between a first position within the path of the card table and a second position outside the path of the card table;
a plurality of manually settable key levers that are movable between an inoperative and an operative position, the key levers having inner ends which, in the operative position, are adapted to hold selected punches stationary with their working ends in said first position during operation of the machine, whereby the card is punched as the card table is moved from the rest position to the working position; and
automatic key elevating means that is optionally settable in a repeat condition and in a cancellation condition, said means being adapted, in the cancellation condition, to engage selected key levers which are in the operative position and return them to the inoperative position during operation of the machine.

10. A machine as claimed in claim 9 wherein the automatic key elevating means comprises a transverse bar that is carried by the frame and which reciprocates inwardly and outwardly during operation of the machine, a plurality of spaced longitudinal levers which are pivotally connected to the transverse bar intermediate their inner and outer ends, a plurality of repeat/cancel levers which are optionally settable in a repeat position and in a cancel position, the repeat/cancel levers when in the cancel condition being adapted to depress the outer ends of related longitudinal levers to thereby raise the inner ends thereof, the raised inner ends of said longitudinal levers being operatively connected to key levers which are in the operative position and adapted to automatically return said key levers to the inoperative position during operation of the machine.

11. A machine as claimed in claim 10 wherein there is 50 a longitudinal lever and a repeat/cancel lever for every group of four key levers, and wherein there is a pivoted key lever actuator for each group, each actuator being engagable with the raised inner end of a longitudinal lever of the group, and each actuator being adapted to return the key levers of the related group from the operative position to the inoperative position when said actuator is engaged by the raised inner end of a related longitudinal lever during operation of the machine.
